P. MURPHY.

FURNACE.

APPLICATION FILED JAN. 11, 1919.

1,415,107.

Patented May 9, 1922.

Inventor
Peter Murphy
By his Attorney
Frederick C. Fischer

UNITED STATES PATENT OFFICE.

PETER MURPHY, OF NEWARK, NEW JERSEY.

FURNACE.

1,415,107.

Specification of Letters Patent.

Patented May 9, 1922.

Application filed January 11, 1919. Serial No. 270,704.

To all whom it may concern:

Be it known that I, PETER MURPHY, a subject of the King of England, residing in the city of Newark, county of Essex, and State 5 of New Jersey, have invented certain new and useful Improvements in Furnaces, of which the following is a full, clear, and exact description, such as will enable others skilled in the art to which it pertains to make, construct, and use the same, reference being had to the accompanying drawings, and to numerals of reference marked thereon, forming a part of this specification.

My invention is applicable to furnaces of 15 various kinds, but is especially adapted for use in heating rivets.

An object of my invention is to produce a complete combustion and as intense heat as can be applicable with the fuel burnt in the 20 furnace.

Another object of my invention is to construct the furnace so that the charges of rivets to be heated may be introduced in the top and taken out at the bottom of the furnace. 25

Another object of my invention is to simplify the construction and operation of the furnace, by decreasing the number of parts of which the usual furnace is composed; by 30 lessening or avoiding the necessity for adjustment of the various parts; by increasing the convenience in manipulation of the furnace.

To this end, I have made changes in this 35 device from similar devices; all with the object of increased efficiency.

With these ends in view, my invention consists in certain novelties of construction and arrangements of parts as hereinafter set 40 forth and pointed out in the claims.

While the preferred form of my invention is illustrated in the accompanying drawings, yet it is to be understood that minor changes may be made without departing from the 45 scope thereof.

In the drawings, in which like numerals of reference indicate corresponding parts throughout:—

Fig. 1 represents a side view, in perspective, of my improved furnace.

Fig. 2 represents a central, vertical, longitudinal section through the furnace, and

Fig. 3 represents a longitudinal section through the furnace, taken on the line α — α .

in Fig. 2, looking in the direction indicated 55 by the arrows.

My improved furnace is mounted upon suitable supports 1 of any improved construction, and is arranged in two compartments, the upper compartment 2 to receive 60 the cold rivets to be heated, and the lower compartment 3 which receives the rivets from the upper compartment and retains them until they are completely heated. The upper and lower compartments of the furnace at one end, are connected by a contracted passage-way 4 for the fire or flame. The peculiar shape of this furnace is not material; but constructed in the form of a rectangle, as is believed to be the most convenient and best adapted to the purpose in practice. 70

The walls 5 are of the usual fire-brick and may be lined with fire clay or other suitable material, if desired. The outside of the furnace may be covered with sheet metal. 75

At the left hand side of the furnace I place a retort 6 also of fire-brick and lined with fire clay or other suitable material, provided with an opening 7 communicating with the 80 lower compartment 3 of the furnace, so that in actual practice the initial fire or flame from the fire-pan 8 can first be introduced into said lower compartment 3 through the contracted passage-way 4 at the end thereof 85 and thence into the upper compartment 2 and thence out through a suitable flue 9 located in the top of the furnace.

Conveniently arranged upon the underside of the retort 6, in any desired or convenient 90 manner, is the fire-pan 8 adapted to hold a moderate supply of suitable fuel supplied by gravity, by means of an oil supply pipe 11, from the tank 10 which for convenience may be located upon the top of the furnace. 95

The retort 6 in three sides thereof, is provided with draft-openings 12, which may be closed by suitable removable means 13, having air-openings such as a perforated fire-brick or the like, to permit the required circulation of air around the fire-pan 8. 100

For ordinary purposes the air currents which pass up and around the fire-pan 8 and through the draft-opening 14 in the bottom of the retort 6 will be sufficient to keep alive 105 the flame in the fire-pan; but in case it is desired to concentrate the draft and force the fire, one or all of the removable means 13

may be removed from the draft-openings 12 for that purpose. When not required to force the fire, the draft-openings 12 may be kept closed as shown in Fig. 1 of the drawings.

The upper compartment 2 of the furnace is provided with a door 18 through which the rivets to be heated are passed into said compartment, and the lower compartment 3 of said furnace is provided, preferably with two doors 15 and 15 through which the finished heated rivets are removed from the lower compartment 3.

The operation of my improved furnace is substantially as follows:—

The valve 16 controlling the oil or other fuel is opened permitting the fuel to be fed by gravity, into the fire-pan 8 where it is ignited. The air circulating around and over the fire-pan into the retort 6, in practice has been found, sufficient to maintain the proper draft and obtain the requisite flame and heat in order to direct and introduce the heat and flame through the opening 7, which 20 communicates with the lower compartment 3 of the furnace, through the lower compartment 3, through the contracted passageway 4 at the end thereof, and thence into the upper compartment 2 of the furnace, and 25 thence out through the flue 9, as clearly indicated by the arrows in Fig. 2 of the drawings. In practice the rivets to be heated are placed in the upper compartment 2 of the furnace and after being partly heated they 30 are passed through the contracted passageway 4 into the lower compartment 3 and left there until completely heated, when they 35 are removed. In this manner a continuous charge of cold rivets is placed into, and a charge of heated rivets, removed from the 40 furnace.

In case it is desired to concentrate the draft and force the fire, one or more of the removable means 13 may be removed from the draft-openings 12 for that purpose.

It will thus be seen that with my improved device I am enabled, by gravity, to feed the oil or fuel to the fire-pan and to utilize the natural draft which is sufficient under 50 ordinary circumstances, to give sufficient heat for the purposes required and that means are provided for concentrating the draft and forcing the fire and flame over the rivets to be heated in the lower and upper compartments of the furnace.

Experience has demonstrated that the organization above described is a highly efficient one, and while I have shown the preferred embodiment of my present invention 55 I do not wish to be limited to the exact details of construction shown and described, as obvious modifications thereof, not in-

volving the exercise of invention, may be made by any skilled mechanic, and such departures from what is herein set forth, I 65 consider within the scope and terms of my claims.

Having thus described my invention, what I desire to secure by Letters Patent is:—

1. In a heating furnace the combination 70 of a furnace casing having an upper and a lower compartment extending lengthwise thereof, connected by a contracted passageway, at one end of the casing, one compartment being provided with an opening for introducing articles to be heated, and the other compartment being provided with an opening for removing such articles, a retort at the other end of the casing having an opening communicating with the lower compartment of the furnace casing, and a flue in the top of the said furnace casing communicating with the upper compartment.

2. In a heating furnace the combination 85 of a furnace casing having an upper and a lower compartment extending lengthwise thereof, connected by a contracted passageway, at one end of the casing, one compartment being provided with an opening for introducing articles to be heated, and the other compartment being provided with an opening for removing such articles, a retort at the other end of the casing having an opening communicating with the lower compartment of the furnace casing, said retort 90 being further provided with draft openings, removable means provided with air-openings located in said openings, and a flue in the top of the said furnace casing communicating with the upper compartment.

3. In a heating furnace the combination 105 of a furnace casing having an upper and a lower compartment extending lengthwise thereof, connected by a contracted passageway, at one end of the casing, one compartment being provided with an opening for introducing articles to be heated, and the other compartment being provided with an opening for removing such articles, a retort at the other end of the casing having an 110 opening communicating with the lower compartment of the furnace casing, said retort being further provided with draft openings, removable means provided with air-openings located in said openings, a fire-pan secured 115 to the lower open end of the retort, and a flue in the top of the said furnace casing communicating with the upper compartment.

This specification signed and witnessed this 4th day of January, 1919.

PETER MURPHY.
